UNITED STATES PATENT OFFICE.

NEWTON S. HILLYARD, OF ST. JOSEPH, MISSOURI.

PAPER-ROLL HOLDER.

Application filed January 21, 1927. Serial No. 162,498.

My invention relates to paper roll holders and more particularly to latching means for locking a shaft in a bracket.

My object is to provide an improved latch member having roll-ejecting and latching parts, and so constructed that the operation which releases the latch results in the ejection of a roll-holder from its engagement in the cabinet.

10 My invention is intended primarily for installation in a paper-roll holder of a particular design, and represents an improvement over the locking or latching means provided by said particular holder which is my 15 invention and is fully described in my Patent No. 1,537,673. I wish to state, however, that I am not restricting my device to use in connection with said holder or any particular type of device, but will claim the structure 20 of a latching means that may be useful in many different situations.

The device which I provide for accomplishing the object stated, and which will be illustrated as associated with a paper roll 25 holder, is installable in a bracket adapted for pivoting a removably journaled body of a class requiring frequent replacement. The invention comprises a pivoted plate having an exterior lever arm, an expanded portion 30 providing an arm normally latching the journals of the said body in pivoted position, and a finger that upon the rotation of the plate for opening the latch to release the journals, is projected against the journals to 35 eject them from pivotal engagement.

The structure and mode of operation of the invention will be particularly described with references to the drawings, in which:

Fig. 1 is a perspective view of my invention installed in a paper roll holder parts of 40 which are broken away.

Fig. 2 is a horizontal cross sectional view through the housing and through part of a core.

45 Fig. 3 is a sectional view on the line 3—3, Fig. 2.

Fig. 4 is a detail perspective view of the locking latch.

Fig. 5 is a fragmentary perspective view of 50 part of one of the housing brackets showing a journal notch for supporting a shaft.

Referring in detail to the drawings:

1 designates a housing comprising back wall 2, end walls 3 and 4 and top wall 5, the housing being open at the front and the bottom and the front being partly framed by an

inverted U-shaped strip 6. Bracket plates 7 and 8 are provided with inturned flanges 9 and 10 on their rear edges of slightly less width than the strip 6 whereby the plates are spaced from the end walls 3 and 4 approximately the width of said strip, the flanges having outturned edges 9' and 10' by which the plates are riveted to the end walls, the front edges of the plates being secured to the strips. The plates 7 and 8 have their lower ends bent back upon themselves outwardly to form upwardly-extending walls 11 and 12 spaced from and parallel thereto and are then bent at right angles outwardly to 70 form stop lips 13 and 14 of width substantially equal to the flanges 9 and 10, the production of the said parallel walls producing the bottom bends 15 and 16 constituting the lower edges of the newly formed double-walled bracket plates, these bottom bends being spaced from the bottom plane of the device. The plates 7 and 8 are slotted from the bottom bends 15 and 16 to provide vertical slits 17 and 18 to receive the ends of the shaft 19, 80 the upper ends of the slits having offset notches 20 and 21 which constitute bearings for the journal ends 22 and 23 of the shaft 19. The shaft 19 extends through a hollow, flat, paper-holding core 24 and is provided with an intermediate enclosed portion offset as at 25 for contact with the sides of the core whereby the shaft is forced to rotate with the core, and whereby the shaft limits the rotation of the core upon engagement of right 90 angularly projecting shaft fingers or cranks 26 and 27 on the ends of the shaft with the stop links or flanges 13 and 14. The core is provided with a weight 28 for returning it to normal position after limited rotation in the 95 process of functioning.

The shaft 19 is introduced into the bearing notches 20 and 21 by the passing of its ends through the slits 17 and 18 and the shifting of the ends for seating in the said offset bearing notches. The structure just described constitutes the bracket and held elements to which my invention is applied.

My present invention comprises means for latching the shaft in pivoted position, which functions also as a means of shifting the shaft into the bearing notches and means of dislodging the shaft from the bearings, as will now be described. I provide latching plate members 29 one of which is shown 105 in Fig. 4 and having a major body portion 30 and a depending wing 31, a lever leaf 110

32 and a handle 33 projecting oppositely to the body portion 30 and having an eccentrically incut neck 34. The inner edges of wing 31 and the lever leaf 32 are so spacedly related that they produce a throat 35 which terminates in a locking socket 36 having a shoulder 37 adjacent the wing and a face 38 adjacent the lever leaf. The plates 29 are provided with pivot openings 39 adjacent the handle portions for the reception of the pivot pins 40 fixed in the bracket plates 7 and 8 and on which the said latching plate members interposed between the bracket plates and the upbent parallel walls, are pivotally mounted, as suggested by the construction eccentrically so, the handles projecting through slots 41 of the flanges 9 and 10. So pivoted, the tendency of the plates is to maintain and return to a position in which the wings 31 are depressed. The plates are mounted in such a position that the lever arms protrude beyond the rear ends of the bracket plates 7 and 8, the sockets 36 may coincide with the offset notches 20 and 21, and the wings 31 close the slits 17 and 18, the plate being restrained by the bearing of the wing 31 on the bent edges 15 and 16 of the bracket plates, as clearly disclosed in Fig. 3. It may be noted in said Fig. 3 that the socket 36 does not circumferentially engage the journals 22 of the shaft 19 but that the shoulder 37 of the socket locks the journal in a notch.

The disclosure by dotted lines in Fig. 3 will assist in describing the mode of operation of the latching plate member. Upon occasion for removal of a core 24, means may be inserted into the housing 1 from beneath to actuate downwardly the handle 33, whereupon the lever leaf 32, being pivoted upwardly, bears upwardly and forwardly against the journal seated in the offset notch 20, and moves the journal out of the notch into the slit 17 through which the journal,

compelled as is the shaft by the weight of the core, falls and the core becomes available for replacement of an element carried. The plate 29 restores itself to normal position through weight of its body portion causing return pivoting upon release of the handle.

The reverse process calls into functioning other features of the latching plate. Upon installing a core in the housing, the journal ends 22 and 23 are projected simultaneously upwardly into the slits 17 and 18, shifting the wings 31 by forcing the plate to pivot; when the journal ends have been elevated to the terminations of the slits and seated in the notches, the plates 29 return to normal position, the shoulders 37 of the sockets 36 engaging the journal ends and preventing accidental egress of the journal ends from the notches.

What I claim and desire to secure by Letters Patent is:

1. In a paper roll holder, a housing having edge slots terminating in offset bearing notches, journals of a paper roll core removably engaged with said notches, and a latch plate pivoted on the housing having an arm normally closing one of said slots and an arm movable against a journal to disengage said journal.

2. In a paper roll holder, a housing having vertical slots terminating in offset bearing notches, a body having journals receivable in the notches and removable through the slots, and latch members pivoted on the housing, a latch member comprising an actuating arm extending within the housing and an arm normally closing one of said slots and having a finger movable across the notch of said slot to disengage one of said journals.

In testimony whereof I affix my signature.

NEWTON S. HILLYARD.
